[57] CLAIM

The ornamental design for a advertising display sign holder, as shown and described.

DESCRIPTION

FIG. 1 is a front perspective view of an advertising display sign holder showing my new design, with the broken line showing for illustrative purposes only and forming no part of the claimed design;

FIG. 2 is a rear elevational view thereof;

FIG. 3 is a front elevational view thereof;

FIG. 4 is a left side elevational view thereof, of which the right side is a mirror image;

FIG. 5 is a bottom plan thereof; and,

FIG. 6 is a top plan view thereof.

FIG. 1

FIG. 5

FIG. 2

FIG. 6

FIG. 4

FIG. 3
